UNITED STATES PATENT OFFICE.

FRANCIS A. LEAVITT, OF PORTLAND, MAINE.

IMPROVEMENT IN TENTS.

Specification forming part of Letters Patent No. 172,882, dated February 1, 1876; application filed May 17, 1873.

To all whom it may concern:

Be it known that I, FRANCIS A. LEAVITT, of Portland, in the county of Cumberland and State of Maine, have invented a new and useful Improved Tent, of which the following is a specification:

In the accompanying drawings, Figure 1 shows the front elevation of the tent with my frame-work applied. Fig. 2 shows the device in a circular frame. Fig. 3 shows the device in rectangular form. Fig. 4 shows the device extended to fit in a company-hospital or large tent.

The object of my invention is to produce a frame-work to be applied to the interior of either a circular or rectangular tent, in order to keep the same properly stretched or distended to increase the facility of striking and setting the tent, and also to render the tent firmer and tighter when pitched.

In the drawings the tent is represented by A and the frame-work by B. This may be made in any convenient form, rectangular, circular, or otherwise, and of any convenient material. I ordinarily use light iron rods, which can be worked easily, joined together at their ends or section-joints firmly, and is of reasonable cost, as well as very durable; but I do not limit myself to any particular metal, or material, or method of working, for metal tubular rods can be advantageously used, and wooden or other frames can be easily and cheaply made for the same purpose I have now in view. This frame-work is placed in the inside of the tent and near the top of the wall, usually at the point where the wall joins the roof part, and now shown at a in the draw-

ing. It may be secured here by fastening it to the canvas by wire, twine, or otherwise, or be affixed or attached to the tent-pole C in any secure manner, so that in either instance it will brace against the tent-eaves at the place aforesaid. This frame-work may be supplied with cross rods or braces, as shown at b, b', b'', and b''', which not only serve as strengtheners, but, on occasion, afford opportunity to suspend articles from, such as clothing, or a lamp, or candlestick, and the like; and, if necessity should require this frame-work to be extended, as for a company or large tent, extra joints B' may be inserted in the sides at convenient points. When this frame is placed in its proper position in the interior of the tent the point of the pole C is placed in the ring a' at the peak, and the pole placed in a vertical position at the center of the floor of the tent. By taking the lower end of the pole in the hand, and passing through the door of the tent, it is allowed to drop gradually to the ground. The tent itself may otherwise be made or constructed in any ordinary or usual manner.

Having thus described my invention, what I consider new, and desire to secure by Letters Patent, is—

A frame or supporter for the eaves of a tent composed of two pieces adapted to receive side sections, and combined with a pole and tent, substantially as and for the purpose specified.

FRANCIS A. LEAVITT.
